CLAIM

Apr. 23, 2012 (JP) 2012-009435

The ornamental design for a tread portion of an automobile tire, as shown and described.

(51) **LOC (10) Cl.** **12-15**

DESCRIPTION

(52) **U.S. Cl.**

FIG. 1 is a perspective view of a tread portion of an automobile tire according to my new design;

USPC **D12/584**; D12/601

FIG. 2 is a front view thereof;

(58) **Field of Classification Search**

FIG. 3 is a top view thereof

USPC D12/544, 545, 579, 580, 582, 583, 584,

FIG. 4 is a right side view thereof;

D12/585, 599, 600, 601, 602, 603;

FIG. 5 is fragmentary enlarged view showing the details of the tread portion thereof;

152/209.1-209.9, 209.11-209.19,

FIG. 6 is a section view taken along line 6-6 in FIG. 5; and,

152/209.21-209.28

FIG. 7 is a section view taken along line 7-7 in FIG. 5.

See application file for complete search history.

In the drawings, the stippled surface shading represents the groove portions of the tread, having the depths illustrated in FIGS. 6 and 7.

(56) **References Cited**

Broken lines in the drawing figures are intended to show portions of the tire that are not being claimed, and thus form no part of the claimed design.
